UNITED STATES PATENT OFFICE

EARL ECKER, OF SPOKANE, WASHINGTON

DESIGN FOR A BED LAMP

Application filed May 1, 1931. Serial No. 39,668. Term of patent 14 years.

To all whom it may concern:

Be it known that I, EARL ECKER, a citizen of the United States, residing at N. 4717 Altamont Street, city of Spokane, county of Spokane, and State of Washington, have invented a new, original, and ornamental Design for Bed Lamps, of which the following is a specification, reference being had to the accompanying drawings, forming a part thereof.

Figure 1 is a view in perspective of the bed lamp.

Figure 2 is a plan view of the bed lamp.

I claim:

The ornamental design for a bed lamp substantially as shown.

EARL ECKER.
